PROTECTION FOR PUMP BEARINGS.

Application filed June 22, 1926. Serial No. 117,675.

This invention relates to supporting bearings of a character suitable for use in pumping equipment employed for the transfer of liquids in which injurious substances are carried. 5 Rotary pumps of the impeller type, in their present advanced stage of development, afford a highly efficient means for transferring liquids in which abrasive materials are carried. Although in this type of 10 pump the wearing parts are of very simple form and the difficulties encountered due to abrasive materials carried in the pumped liquids are not so pronounced as found in other types of pumps, the bearings of these 15 rotary or centrifugal pumps are, in their present form, still subject to the detrimental influences of substances carried into the space between the bearing surfaces by what shall be hereinafter termed localized circuits, 20 which result from the differences in pressure encountered at the opposite ends of the bearing members in this type of pump.

Each impeller section, or stage, of a rotary pump receives the transferred liquid at one 25 pressure and delivers this liquid at a higher pressure to the next impeller section or to the discharge outlet of the pump; therefore, it is recognized that the action in the pump is not in the form of a gradual increase in 30 the pressure applied to drive the liquid, but is rather in the form of a series of consecutive steps through which the water pressure is raised by the successive impeller sections. Owing to the fact that the bearings which 35 support the impeller shaft are situated between the consecutive impellers, it follows, when the pump is in operation, that the liquid pressure existent at the two ends of each bearing vary in accordance with the 40 inlet pressures and discharge pressures of each respective impeller section. The marked difference in pressure at the two ends of the bearing results in a return flow or circulation of liquid through the bearing and 45 the consequent conducting into the bearing of whatever material may be carried in suspension or solution in the liquid being pumped.

An extensive use to which pumps of this 50 type are applied, is the lifting of water from wells. Sand carried in the well water is conducted into the bearings in the manner

hereinabove stated, and in passing through the bearings this sand produces a grinding or cutting action on the bearing surfaces, 55 and the sand thus passing through the bearing has a tendency to grind the shaft and the bushing forming the bearing to such an extent that the bushing ceases to perform the functions of a bearing, with the ultimate 60 result that the operating efficiency of the pump is impaired to such an extent that the pump must be dismantled and the bearings replaced. In rotary pumps of the impeller type, the principal wear is confined to the 65 bearings. By reducing this wear to a minimum, the effective life of such pumps may be extended to an almost indefinite period.

It is an object of the invention to provide a rotary pump having shaft supporting bearings of a form adapted to exclude from the 70 wearing surfaces of the bearing, those localized circuits or currents of the liquid being pumped which are characteristic of rotary pumps as hereinbefore mentioned, thus eliminating the rapid wearing away of the bearing structure due to the abrasive action of the sand, fine particles of quartz, or the like, 75 which may be carried in the liquid being pumped.

It is also an object of the invention to provide a new form of bearing structure for pumps of the character described, which in addition to other valuable features will serve to improve and simplify the manufacture of 80 rotary pumps in at least three additional ways, as follows.

First: The invention enables the localization of wear to relatively small and simple parts and provides for facility and economy 85 in replacement of these parts.

Second: The invention provides for the use of metals especially adapted to the specific manners of employment. The impellers, being subjected to intense centrifugal 90 stresses, must necessarily be made from materials having maximum tensile strength and minimum tendency toward crystallization, whereas the casing and the bearing parts must each be constructed of metals particularly suitable for each separate usage.

Third: The invention provides for standardization of bearing parts used in a large 100 number of pumps, this element contributing

to simplification of manufacturing practice and the consequent reduction of manufacturing costs.

Further objects and advantages will be made evident hereinafter.

Referring to the drawing which is for illustrative purposes only,

Fig. 1 is an elevational sectional view through a portion of a rotary pump of common screw design, this view showing a preferred form of the present invention.

Fig. 2 is a fragmentary section taken on a plane represented by the line 2—2 of Fig. 1, showing the simple manner in which relief passages are provided in the bearing member.

The form of rotary pump shown in the accompanying drawing is the well known screw impeller type, in which the liquid being transferred is forced along parallel to the impeller drive shaft 11, as indicated by arrows 12, by the impact or screw action of the helical impellers 14 which are equipped with helically formed impeller blades 15 through which the driving of the liquid is accomplished. The shaft 11 which carries the impellers, one of which impellers is shown at 14, is supported in a casing 16 which is made up of consecutive co-operating sections 17, each one of which casing sections has a centrally disposed bearing boss supported by radially extending stationary vanes 19.

It has been previous practice in the construction of pumps of this character to use the surface of the shaft, such as 11, to form a bearing in conjunction with the inner surface of the bore through the bearing boss 18. The difference in pressures at the two ends of the bearing results in a circulation of liquid downward between the bearing surfaces as indicated by the arrows 20, with the result that abrasive substances carried in the liquid are brought in contact with these bearing surfaces and a very rapid wearing away of the bearing surfaces results. The grinding action of the abrasive materials reduces the diameter of the shaft, which makes very difficult the installation of new bearing bushings, and allows the impellers to run out of alignment.

In the present invention the shaft 11 extends through a sleeve 21 which fits fairly closely upon the shaft, but is not, however, the bearing for the shaft. The bearing for the shaft 11 is formed from two elements, a stationary bushing or shell 25 fitted within a counterbore 26 in the lower end of the bearing boss 18, and a rotating bearing member 27 which is fitted into the bore 29 of the impeller hub 30. It will be noticed that the bearing member 27 is in the form of a sleeve which preferably extends entirely through the hub 30 of the impeller 14, and the projecting end 31 thereof is

counterbored at 33 to a depth substantially equal to the distance that the bearing member projects from the impeller. The sleeve 21 projects into the counterbore 26 of the bearing boss 18 and stops at a point near the bottom 35 of the counterbore 33 in the end of the rotating bearing member 27.

In the projecting end of the bearing member 27, on a plane substantially coincident with the bottom 35 of the counterbore 33 as indicated by the line 2—2 of Fig. 1, radial passages 38 are provided in the form of drilled holes. The bearing member 27 and its supported impeller 14 are securely held on the shaft 11 in any suitable manner, such as by the use of a gib key 40 arranged to fit into suitably formed key-ways in the shaft 11, the member 27, and the hub 30 of the impeller 14.

The localized circulation of liquid, as indicated by arrows 20, passes through the space between the shaft 11 and the sleeve 21, from the upper end 41 of the sleeve 21 to its lower end, which lower end of said sleeve is directly adjacent to the radial passages 38 which communicate between the space surrounding the shaft 11 and the space between the boss 18 and the impeller hub 30, which space in turn communicates with the liquid channels of the pump. The sleeve 21 directs the localized circulation down substantially to the bottom of the counterbore 33, whereat this localized flow passes directly and freely outward through the passages 38, and the tendency for the entry of harmful substances into the space between the bearing faces is minimized. The action of the sleeve 21 is to throttle down the flow of liquid constituting the localized circulation, and to direct this throttled flow by the upper end of the bearing so as to prevent the flow of liquid and detritus from entering the space between the contacting bearing surfaces.

The clearance between the shaft 11 and the sleeve 21 is relatively small. By keeping the area of the space through which the localized circulation must flow very small, an effective throttling action is obtained. On reaching the space at the lower end of the sleeve 21 this flow may pass freely out through the passages 38; therefore there is no tendency toward a flow of liquid through the space between the end 31 of the rotating bearing member and the shell 25, which space is between the bearing surfaces of the bearing members 25 and 27.

The throttle sleeve 21 forms a dividing wall and does not support the shaft 11, but in addition to forming a dividing wall has the function of holding the flow of the localized circulation of liquid to a minimum amount. When the throttle sleeve is first placed in operation, it may fit quite closely on the shaft 11, but after the pump has been

in operation for a short period of time, it will be found that the cutting action of the sand carried through the sleeve by the flow of liquid will cause a readjustment of the 5 sleeve and shaft diameters to provide the

correct throttle opening which will permit the passage of sand particles carried in the liquid but will at the same time keep the flow of liquid throttled down to a minimum.

10 Owing to the fact that the shaft 11 is held centralized in the sleeve by the bearing formed by the members 25 and 27, there is then no further enlargement of the throttling passage.

15 Although the throttle sleeve 21 is shown as manufactured separately from the remainder of the casing structure, it, however, when in position of operation, becomes part of the casing structure and forms a dividing wall between the shaft opening and the annular bearing recess into which the hollow rotating bearing portion 31 of the member 27 extends. This bearing member 27 although of removable character, becomes 20 a part of the impeller 14 when pressed into the impeller hub 30, so that the extending end 31 may then be considered as a tubular bearing extension of the impeller.

25 Previously herein has been indicated the fact that the chief cause of wear in these pump bearings has been found in the entrance of abrasive materials into the space between the wearing surfaces; therefore, by minimizing or eliminating this entrance of 30 foreign substances into the contacting bearing space, the useful life of the bearing is greatly lengthened and an important step toward the perfection of devices for pumping materials containing abrasive and other harmful substances is accomplished.

35 With a view to making this disclosure of the invention as brief and simple as possible, only one embodiment of the invention has been shown and described. The scope 40 of the invention is not, however, limited by the simplicity of this showing, but may be embodied in other designs and forms without departing from the spirit of the invention set forth in the following claims.

45 We claim as our invention:

50 1. In an invention of the character described, the combination of: a shaft; casing supporting said shaft, said casing having a shaft opening through which said shaft extends, and having an annular bearing recess concentric with and separated from said shaft opening by an annular wall which extends substantially the full length of the outer wall of said recess; a bearing member 55 mounted on said shaft having a tubular portion extending into said bearing recess and making bearing engagement with the outer wall of said recess, and having radial openings near the inner end of said tubular

portion of a size permitting the localized 65 circulation to pass radially outwardly through said radial openings from said shaft opening and past the end of said bearing recess.

2. In an invention of the character described, the combination of: a shaft; casing supporting said shaft, said casing having a concentric shaft opening through which said shaft extends and having a concentric annular bearing recess open at one end and 70 separated from said shaft opening by an annular wall extending substantially to the open end of said bearing recess; a bearing member mounted on said shaft adjacent to said annular bearing recess, having a tubular 75 portion extending into said bearing recess and making bearing engagement therewith, and having radial openings near the inner end of said tubular member of a size permitting the localized circulation to pass 80 freely from said shaft opening and past the end of said bearing recess.

3. In an invention of the character described, the combination of: a shaft; casing supporting said shaft, said casing having 90 a bearing counterbore; an impeller; a bearing member having said impeller mounted on one end thereof, the other end of said bearing member being counterbored to a depth substantially equivalent to the extension of said bearing member from said impeller, and having radial openings near 95 the bottom of its counterbore; and a tubular wall member extending from said casing into and substantially to the bottom of said 100 counterbore in said bearing member.

4. In an invention of the character described, the combination of: a shaft; an impeller; a sleeve for mounting said impeller on said shaft; and a key member engaging 105 between said shaft, said sleeve and said impeller.

5. In an invention of the character described, the combination of: a shaft; casing receiving said shaft, said casing having an 110 annular bearing recess concentric with and separated from the shaft opening by an annular wall of substantially the same extension as the outer wall of said annular bearing recess; impeller means having a tubular 115 bearing portion extending into said bearing recess, said tubular bearing surrounding said inner wall of said bearing recess and having radial openings therein positioned at the end of said inner wall whereby the localized circulation will pass outwardly from the end of said inner wall through said 120 radial openings.

Signed at Los Angeles, California, this 28th day of May 1926.
